UNITED STATES PATENT OFFICE.

CHARLES MORLET, OF JERSEY CITY, NEW JERSEY, ASSIGNOR OF ONE-HALF TO PROSPER NORDMANN, OF NEW YORK, N. Y.

PUSH-BUTTON FOR REPEATING-WATCHES.

SPECIFICATION forming part of Letters Patent No. 367,995, dated August 9, 1887.

Application filed November 30, 1886. Serial No. 220,257. (No model.)

To all whom it may concern:

Be it known that I, CHARLES MORLET, of Jersey City, in the county of Hudson, State of New Jersey, have invented certain new and useful Improvements in Push-Buttons for Repeating-Watches, of which the following is a specification.

This invention has reference to a push-button or slide-piece for actuating the sounding mechanism of repeating-watches, said slide-piece being capable of ready insertion into the watch-case without requiring the special fitting of the parts to the same to each individual case; and the invention consists of a push-button for repeating-watches which is composed of a slotted filling-piece of segmental shape that is soldered or otherwise attached to a corresponding recess of the watch-case center, of an exterior slide-piece having a nose for the finger, and an interior slide-piece connected to the exterior piece by a screw, said interior slide-piece being guided along a fixed arc-shaped arm of the main piece and acted upon by a spiral spring interposed between the supporting-socket of said arm and the end of the interior slide-piece, as will be fully described hereinafter, and finally be pointed out in the claims.

In the accompanying drawings, Figure 1 represents a front elevation of a repeating-watch with my improved push-button for operating the sounding mechanism of the same. Fig. 2 is a vertical longitudinal section of the push-button shown inserted in the case and drawn on a larger scale. Fig. 2^a is a side view of the push-button shown as detached from the case; and Fig. 3 is a vertical transverse section on line *x* *x*, Fig. 2.

Similar letters of reference indicate corresponding parts.

Referring to the drawings, A represents the main or filling piece of my improved push-button for repeating-watches. The filling-piece A is made of segmental shape, and arranged to be inserted into a slot, *a*, of corresponding shape, which slot is arranged at any suitable point of the watch-case center, as shown in Fig. 1. The main or filling piece A is soldered, screwed, or otherwise attached to the watch-case center, so as to be firmly retained in the

slot of the same. The filling-piece A is provided at its middle part with a slot, *a'*, which slot serves to guide a screw, *d*, that connects the exterior slide-piece, B, with the interior slide-piece, C, which together form the push-button of the repeating attachment of the watch. The exterior slide-piece, B, is provided with a projection or nose, *d'*, against which the finger is placed when actuating the push-button and repeating device. The inner slide-piece, C, is provided with a perforated lug, *b*, at one end and guided along a fixed arc-shaped arm, *f*, that is attached to a fixed socket, *f'*, of the main piece A. A spiral spring, *g*, is placed on the guide-arm *f* and interposed between the socket *f'* and the perforated end lug, *b*, of the inner slide-piece, C, said spring serving to return the slide-pieces B and C and the connecting-lever of the repeating attachment to their normal positions as soon as the pressure of the finger on the exterior slide-piece is relaxed. By pushing the exterior slide-piece with the finger the spiral spring *g* is compressed until the connecting-screw *d* arrives at the end of the slot *a'*, the spring returning the slide pieces into their normal position on returning into its expanded condition.

My improved push-piece or slide-button for repeating-watches has the advantage that it can be conveniently fastened and inserted into the centers of watch-cases without the loss of time required in attaching the parts of the push-button to the watch-case center, as was required by the practice heretofore in use.

In case any part of the push-button should get out of order, it can be readily detached from the case, so as to be repaired in a convenient manner, without interference with the movement. When the movement with the repeating attachment is inserted into the case, the actuating-lever of the attachment is attached in any approved manner to the interior slide-piece, C, of the push-button, as indicated in dotted lines in Fig. 2, and detached from said slide-piece when the movement is to be removed from the case for repairs or otherwise.

Having thus described my invention, I claim as new and desire to secure by Letters Patent—

1. A push-button for repeating-watches, consisting of a slotted main or filling piece, an

interior spring-actuated slide-piece, an exterior slide-piece, and a screw for connecting said slide-pieces, substantially as set forth.

2. A push-button for repeating-watches, consisting of a slotted main or filling piece, an exterior slide-piece having a projecting nose, an interior slide-piece, a screw connecting the exterior and interior slide-pieces, an arc-shaped guide-arm passing through the perforated end of the inner slide-piece, and a spiral spring located on said arm and acting on said interior slide-piece, substantially as set forth.

3. The combination, with a watch-case cen-

ter having a slot at one point of the case, of a detachable push-button composed of a filling-piece fitted into said slot, an interior spring-actuated slide-piece, an exterior slide-piece, and a screw for connecting said slide-pieces, substantially as set forth.

In testimony that I claim the foregoing as my invention I have signed my name in presence of two subscribing witnesses.

CHARLES MORLET.
